(57) **CLAIM**

The ornamental design for a folding lock, as shown and described.

DESCRIPTION

This file of this patent application file contains at least one drawing/photograph executed in color. Copies of this patent with color drawing(s)/photograph(s) will be provided by the Office upon request and payment of the necessary fee.

FIG. 1 is a front elevational view of a folding lock showing my new design;

FIG. 2 is a bottom plan view thereof;

FIG. 3 is a rear elevational view thereof;

FIG. 4 is a top plan view thereof;

FIG. 5 is an enlarged right side elevational view thereof;

FIG. 6 is an enlarged left side elevational view thereof;

FIG. 7 is a bottom left perspective view thereof;

FIG. 8 is a bottom right perspective view thereof;

FIG. 9 is a top perspective view thereof;

FIG. 10 is a front elevational view of a second embodiment of a folding lock;

FIG. 11 is a bottom plan view of FIG. 10;

FIG. 12 is a rear elevational view of FIG. 10;

FIG. 13 is a top plan view of FIG. 10;

FIG. 14 is a bottom left perspective view of FIG. 10;

FIG. 15 is a top perspective view of FIG. 10; and,

FIG. 16 is a top right perspective view of FIG. 10.

FIGS. 10-16 are color photographs of the claimed design.
